CLAIM

The ornamental design for a built-in wine refrigerator, as shown and described.

DESCRIPTION

1. Built-in wine refrigerator

1.1 : Perspective

1.2 : Front

1.3 : Back

1.4 : Left, the right being a mirror image thereof

1.5 : Top

1.6 : Perspective view in which the claimed design is installed on a wall

The broken lines depict portions of the built-in wine refrigerator that form no part of the claimed design; the dash-dotted broken lines define the boundary of the claimed design and form no part thereof; the portions of reproduction 1.6 in dash-dot-dot broken lines show environmental structure.

(Continued)

ture only and form no part of the claimed design; this design is for a built-in wine refrigerator made of glass, synthetic resin and metal.
